BUFFING-GEAR FOR RAILWAY-CARS.

1,323,787.

Specification of Letters Patent.

Patented Dec. 2, 1919.

Application filed October 1, 1915. Serial No. 53,626.

To all whom it may concern:

Be it known that we, WILLARD F. RICHARDS and DONALD C. DAVIS, citizens of the United States, residing at Depew and Buffalo, respectively, in the county of Erie and State of New York, have invented a new and useful Improvement in Buffing-Gears for Railway-Cars, of which the following is a specification.

10 This invention relates to buffing gears for railway cars and more particularly to friction buffing gears for use with the platform buffers of railway passenger cars.

The cars of a train are adapted to move 15 toward and from each other to the extent permitted by the yielding draft gears coupling the cars together, and in order that the platform buffers on the adjacent cars may be retained always in contact or prevented 20 from separating so as to leave a space between them in which one's foot could be caught and injured, the buffers are so arranged relative to the car couplers that they are projected outwardly by their 25 springs when the cars are uncoupled beyond the position which they occupy when the cars are coupled. The buffers, therefore, have to be shoved inwardly toward the cars and their operating springs compressed 30 when coupling the cars together, and in the movements of the cars away from each other the buffers will be moved outwardly by their springs and be retained in contact. Ordinarily, the couplers have a travel of two 35 and one half inches both inwardly and outwardly from the intermediate position which they occupy when the cars are coupled together, and the buffers should be arranged to move a corresponding distance.

40 The object of the invention is to produce a friction buffing mechanism of simple and practical construction in which the friction producing elements have a free or non-friction-producing action sufficient to permit 45 the movements of two coöperating buffers necessary for coupling two cars together and retaining the buffers in contact, and which operates to produce the required friction to resist buffing shocks which force the 50 buffers inwardly beyond the position normally occupied by them when the cars are coupled.

In the accompanying drawings:—

Figure 1, is a plan view partly in section 55 of a platform buffer for passenger cars pro-

vided with a buffing gear embodying the invention, and showing the parts in the normal position which they occupy when the cars are uncoupled.

Fig. 2 is a sectional elevation thereof in line 2—2, Fig. 1.

Fig. 3 is an enlarged view similar to Fig. 1, showing the positions occupied by the parts when two cars are coupled together.

Fig. 4 is a cross section of the buffing gear 65 in line 4—4, Fig. 1.

A represents a portion of the platform frame of a passenger car; B the platform buffer, and C the coupler, all of which may be of any usual or suitable construction and 70 arrangement. The buffer, as usual, is provided with a center stem b and pivoted side stems b' passing through guide openings in the platform endsill a, and righting springs b² acting on the side stems b' hold the buffer 75 yieldingly in a position parallel with the end sill a. The drawbar or shank c of the coupler is connected to any suitable draft and buffing gear (not shown). Fig. 1 shows the normal position of the buffer, or position which it occupies when the cars are uncoupled, and Fig. 3 shows the position normally occupied by the buffer when two 80 cars are coupled together.

The buffing gear, in the construction 85 shown, comprises a box or case D, which is stationarily supported back of the end sill a and has an open end facing the end sill; a follower E, which is adapted to be engaged and forced toward the open end of the box 90 or case by the inner end of the central buffer stem b; wedge or friction blocks F which are adapted to be moved lengthwise in the box or case by the movement of the follower 95 toward the box or case and are provided with inclined faces f adapted to engage co-operating converging friction faces G in the box or case D by which the wedge or friction blocks are moved laterally toward each other; and a spring H, preferably composed 100 of bowed spring plates, arranged lengthwise between the wedge blocks, which resists the lateral movement of the wedge blocks by the converging faces in the box or case. In the normal or outward position of 105 the wedge blocks F, shown in Fig. 1, their inclined faces f are out of contact with the converging friction faces G and the wedge blocks are therefore adapted to move inwardly in the box or case without lateral 110

movement until their inclined faces are brought into contact with the inclined friction faces G. This movement of the wedge or friction blocks, which is sufficient to permit the coupling of two cars is resisted by one or more springs I arranged in the box or case and acting outwardly against the wedge blocks, preferably through the medium of a plate or follower K extending 5 cross wise in the box or case between the inner ends of the wedge or friction blocks and the springs I. In the further inner movement of the wedge blocks the converging friction faces G, acting against the inclined faces f of the wedge blocks force 10 the wedge blocks laterally toward each other and compress the spring H and the friction thus produced between the friction faces G and the wedge blocks coöperates 15 with the springs I in resisting such further inward or buffing movement of the wedge blocks and the buffer B. There are preferably two of the springs I, which are coil springs, arranged side by side in the box or 20 case D, and they are of sufficient strength to offer the desired resistance to the coupling movement of the buffer from its normal outer position shown in Fig. 1 to the position shown in Fig. 3. In addition to 25 the springs I, two short coil springs i are preferably arranged in the springs I. These short springs i act in conjunction with the springs I in resisting the continued or buffing movement of the buffer inwardly 30 beyond the position shown in Fig. 3, and the springs I and i together are strong enough to exert the necessary force to release the wedge blocks from engagement with the friction faces G.

35 40 The wedge blocks are wedge shaped for only a portion of their length and are straight faced, or not inclined from the inner ends of their inclined faces f to the inner ends of the blocks. In order to guide 45 the wedge blocks and prevent them from rocking on the springs H during the coupling movement thereof before the friction faces engage, the blocks are preferably provided at opposite sides with straight edged 50 ribs L adapted to slide in corresponding guide grooves l in the box or case D at the opposite side of the friction faces G. These ribs also strengthen the thin ends of the wedge blocks. l' indicates lips at the inner 55 ends of the wedge blocks adapted to engage shoulders l² in the box or case D at the inner ends of the friction faces G for preventing the accidental escape of the wedge blocks and spring H from the open 60 end of the box in the case.

As shown, the buffing gear is supported in a chamber formed by a central integral extension M of the end sill a with the inner end of the box or case D abutting against 65 the end wall m of said extension and with

the follower E in position to be engaged and forced toward the box or case by the inner end of the central buffer stem b, but manifestly the gear could be mounted in any other suitable supporting structure and it 70 can be reversed end for end with the follower E against the end wall m or other suitable abutment and with the box or case D arranged to be engaged and forced toward the follower by the stem b. 75

While a box or case, such as the box D described which contains the movable parts of the gear and is provided with the friction faces G, is preferably employed, such a box or case is not absolutely essential to the invention, since other constructions could be employed in which the friction faces G are arranged and coöperate with the inclined faces of the wedge blocks to allow the free coupling movement thereof in the manner 80 explained. 85

We claim as our invention:

1. A friction gear comprising wedge blocks having inclined faces at one end thereof and straight longitudinal guide 90 portions at the other end thereof, converging friction faces which are normally out of contact with and are adapted to engage the inclined faces of said wedge blocks to cause the same to move laterally after said 95 wedge blocks have moved longitudinally through a predetermined distance, guide faces on which said guide portions of the wedge blocks slide for guiding said blocks during their longitudinal movement through 100 said predetermined distances, when the inclined faces of the wedge blocks are not in contact with said converging faces, said friction faces and guide faces extending lengthwise of said gear and being arranged 105 side by side, a spring which normally holds said inclined and friction faces out of contact and resists the longitudinal movement of said wedge blocks, and a spring which resists the lateral movement of said wedge 110 blocks. 115

2. A friction gear comprising a box open at one end and provided with inwardly converging friction faces and longitudinal guide faces, said friction faces and guide 120 faces extending lengthwise of the box and being arranged side by side, wedge blocks which have inclined faces at their outer portions that are normally out of contact with and are adapted to engage said converging 125 faces of the box after said blocks have moved longitudinally through a predetermined distance, and longitudinal guide faces at the inner portions of said wedge blocks which slide on said guide faces of the box 130 to guide said wedge blocks when the wedge blocks are not in contact with said converging faces, a spring which resists the longitudinal inward movement of said wedge blocks and normally holds the inclined faces 135

- of the wedge blocks out of contact with said converging faces, and a spring between said wedge blocks which resists movement of said wedge blocks toward each other due to 5 the engagement of said converging faces with said inclined faces of the wedge blocks.
3. A friction gear comprising a box open at one end and provided with inwardly converging friction faces and longitudinal guide 10 grooves at opposite sides of said friction faces, wedge blocks which are movable longitudinally in said box and have inclined outer faces adapted to engage said converging faces of the box when said wedge blocks 15 are forced inwardly in the box, and longitudinal guide ribs at opposite sides of said inclined faces adapted to move in said guide grooves, a spring which resists the longitudinal inward movement of said wedge 20 blocks and normally holds the inclined faces of the wedge blocks out of contact with said converging faces, and a spring between said wedge blocks which resists movement of said wedge blocks toward each other due to 25 the engagement of said converging faces with said inclined faces of the wedge blocks.
4. A friction gear comprising a box open at one end and provided with inwardly converging friction faces, guide grooves at
- opposite sides of said friction faces, and 30 shoulders at the inner ends of said converging faces, wedge blocks which are movable longitudinally in said box and have inclined outer faces adapted to engage said converging faces of the box when said wedge blocks 35 are forced inwardly in the box, longitudinal ribs at opposite sides of said wedge blocks which move in said guide grooves, and shoulders at the inner ends of the wedge blocks adapted to engage said shoulders in 40 the box to prevent displacement of the wedge blocks from the box, a spring which resists the longitudinal inner movement of said wedge blocks and normally holds the inclined faces of the wedge blocks out of 45 contact with said converging faces, and a spring between said wedge blocks which resists movement of said wedge blocks toward each other due to the engagement of said converging faces with said inclined faces of 50 the wedge blocks.

Witness our hands this 29th day of September, 1915.
